UNITED STATES PATENT OFFICE.

HARRY CHILINGIRIAN, OF BRIDGEPORT, CONNECTICUT.

SAFETY GAS STOVE WITH KITCHEN CABINET.

1,426,547.

Specification of Letters Patent. Patented Aug. 22, 1922.

Application filed August 23, 1921. Serial No. 494,464.

To all whom it may concern:

Be it known that I, HARRY CHILINGIRIAN, a citizen of Armenia, residing at Bridgeport, county of Fairfield, State of Connecticut, have invented an Improvement in Safety Gas Stoves with Kitchen Cabinets, of which the following is a specification.

This invention relates to gas stoves and particularly to gas cook stoves and has for 10 an object to provide a stove of this type which will be reliable and efficient in operation and which will be simple in construction and comparatively cheap and easy to manufacture.

15 In the preferred form the invention comprises a supporting cabinet or stand comprising supporting legs with top, bottom, end and side walls enclosing the space between the legs, which space is accessible 20 through suitable doors. Mounted upon the top of the supporting cabinet is a gas plate carrying one or more burners surrounded by sheet metal walls connected at the corners by means of sliding joints so that they may 25 be easily put together and taken apart, if desired, and with a retractable cover plate over the burners.

Referring to the accompanying drawings, Fig. 1 is a perspective view of my stove, 30 part being broken away to more clearly disclose the structure.

Fig. 2 is a transverse sectional elevation.

Fig. 3 is a partial plan and a partial sectional view of the front wall of the supporting cabinet.

Fig. 4 is a sectional plan view of the end wall of the supporting cabinet.

Fig. 5 is a detailed view of the bottom and back walls of the cabinet.

40 Fig. 6 is a top plan view of the walls surrounding the burners showing the method of securing them together.

Fig. 7 is a detailed view of the top portion of the stove.

45 Fig. 8 is a side elevation of the cover plate for the burners.

Fig. 9 is a detailed sectional view at one corner of the top of the supporting cabinet.

50 Figs. 10 and 11 are detailed sectional views of the walls forming the frame for the top of the cabinet.

Fig. 12 shows a slight modification of the structure for the top section of the stove.

55 Fig. 13 is an elevation of the side of the frame removed.

Fig. 14 is a detailed section, line 14—14 of Fig. 2, and

Fig. 15 is a detailed section of the ornamentation at top edges of the walls of the upper section.

60

The lower half or base portion of the stove comprises a supporting cabinet preferably rectangular in shape and provided at each corner with a supporting leg 20. Suitable side and end members 21 and 22, respectively, are secured to the legs at the upper ends thereof to hold them together and form a frame. The end members 22 are secured to the legs by means of two bolts 23 while the side members 21 are secured to 70 the legs by a single bolt 24. This allows the legs at either end to be folded into the frame about the bolts 24 as pivots, shown in Fig. 13, the sides 21 extending across the ends of members 22, as shown in Fig. 3. The legs 75 are connected a suitable distance above the floor by suitable end bars 25 which are fastened between two legs and are preferably glued and doweled thereto, as shown at 26 in Fig. 2. These bars are rabbeted at 27 to 80 form a seat for the ends of the bottom 28 of the cabinet. To the rear edge of the bottom member 28 is hinged a back comprising two sections 29 and 30 hinged together at 31. Also hinged to the upper edge of 85 lower section 29 but on the opposite side from the hinges for the section 30 is hinged a shelf 32 which when in assembled position is supported by suitable brackets 33. In transporting the stove the bottom 28 and 90 the back 29 and 30 may be removed from the supporting cabinet and folded, as indicated in Fig. 5, the top section 30 being folded back on the lower section 29, the shelf 32 moved into alignment with the section 29 95 and then the back and bottom folded together.

The end walls of the cabinet are composed of any suitable construction preferably as shown with a panel 34 and vertically 100 arranged spaced slats 35. The front wall is practically of the same construction but is formed in two sections, each section being a sliding door 36 provided with supporting wheels 37 running on tracks 38 on the upper 105 side of the bar 39 extending between the two front legs. Suitable guides 40 are also provided on the bar 41 extending between the legs at the upper ends thereof, these guides running in grooves on the top edges of the 110

doors. These doors, however, instead of being slidably mounted may be hinged if desired, although the sliding arrangement is more desirable. Within the cabinet may 5 also be mounted one or more drawers 42 mounted to slide on suitable supporting members 43.

The upper section of the stove is mounted on top of the supporting cabinet and is made 10 of sheet metal comprising a bottom wall 44, front wall 45, rear wall 46 and end walls 47. These walls are preferably secured at the corners, as shown in Figs. 6 and 7, the vertical edges of the rear wall being bent back 15 upon the body at 46', the front wall 45 being left straight but having secured on the inner side thereof plates 48 bent upon themselves at 49. This front plate is left straight to improve the appearance of the stove from 20 the front. The end walls 47 are bent at right angles at their vertical edges and then folded inwardly on themselves at 49. The bottom edges of these walls 47 are also bent in a similar manner, as shown at 50 in 25 Fig. 7, the ends of the bottom wall 44 being bent upon themselves at 51 in Fig. 7. In assembling, the curved walls at 50 and 51 of the walls 47 and the bottom wall 44 are placed in locking position by sliding one 30 into the other. Then the back 46 and the front 45 are slid downwardly from the top with the bent portions 46'-49 and 48-49 interlocking, as shown in Figs. 6 and 7. This whole top portion may then be placed 35 upon the top of the supporting cabinet and secured thereto by any suitable means such as screws passing through the bottom 44 into the tops of the legs or the bar 41.

A gas plate 52 is supported on this bottom 44 and may be of any suitable construction. Preferably a frame work, as shown, lies on suitable legs 53 and carries any desired number of burners 54 under the grids 54', the burners being supplied with gas 45 from a pipe 55 and suitable controlling valves 56. It will be noted the gas plate and burners are completely surrounded by the sheet metal walls of the top section of the stove so that they are protected from 50 drafts and are not likely to be accidentally extinguished thereby.

In order that the burners may be covered when not in use I mount a cover plate 57 thereover, this plate filling substantially the 55 entire space between the side and end walls of the top section. It is mounted so that it may occupy a horizontal position over the burners, as shown in full lines in Figs. 1 and 2, to cover the burners and also to 60 provide a convenient shelf, or it may be retracted to a position at the rear of the burners against the rear wall 46, as shown in dotted lines in Fig. 2. I accomplish this result by securing in the corners, between 65 the rear walls 46 and end walls 47, suitable

brackets or angle members 58 which have wings 59 and 60 secured to the rear and end walls, the wings 60 being formed with an L-shaped slot 61, the short or horizontal leg being at the upper end thereof. The 70 rear edge 62 of the cover plate 57 is bent over a rod 63, the free ends of the rod extending through the slots 61. The front edge of the plate 57 is bent downwardly at 64 and when this plate is in the horizontal 75 position it rests upon the upper edge of the front wall 45. When it is desired to move the cover plate to its vertical out of the way position, the front edge 64 is lifted, the whole plate pushed backwardly until 80 the ends of bar 63 reach the upper ends of the vertical portions of the slots 61, when they move downwardly therein allowing the plate 57 to rest against the rear wall 46, as shown in dotted lines Fig. 2. When it 85 is desired to bring this plate to a horizontal position, a reverse action is necessary, the rod 63 being drawn upwardly in the slot 61 until it reaches the top thereof when it is drawn forwardly in the short horizontal 90 portion and the front edge 64 placed upon the upper edge of the front 45. If desired a second shelf 65 may be supported from the end walls of the upper section by suitable angle irons as 66. Also the upper 95 edges of the rear and end walls may be finished with any suitable ornamentation, such as a U-shaped edge binder 67, as shown in Fig. 15.

As the side and end members 21, 22, connecting the tops of the legs 20, are preferably of wood, at the ends thereof I insert suitable strengthening members 68, where the bolts 23 and 24 pass through these members, to prevent their splitting. These 100 inserts are preferably flat pieces of wood inserted between the tongues 69 and 70 with the grain running at right angles with the grain of members 21 and 22, and glued in 105 position.

Instead of securing the edges of the bottom and end walls by bending, as shown in Fig. 7, they may if desired be hinged together, as shown at 69 in Fig. 12. This allows the end walls to be folded down upon 110 the bottom walls without disconnecting them.

It will be apparent from the foregoing description that I have devised a very efficient gas cook stove which is simple in 115 construction and may, therefore, be easily and cheaply manufactured. Also, because of the manner of mounting the burners, they are protected from drafts which might accidentally extinguish the same thus securing the maximum of safety.

Having thus set forth the nature of my invention, what I claim is:

1. In a gas stove, a support, a gas plate including burners mounted on said support, 120

- back and end walls around said plate, and a retractable cover plate over the gas plate and burners adapted to be moved to a position to the rear of the burners and between the same and the rear wall.
2. In a gas stove, a support, a gas burner on said support, a cover plate over the burner, brackets located to the rear of the burner provided with L-shaped slots, and means on the cover plate pivotally and slidably mounted in said slots, and so arranged that the cover plate may be placed in a horizontal position over the burner or be moved to an upright position to the rear thereof.
3. In a gas stove, a support, burners mounted on the support, back, end and front walls surrounding said burners and comprising sheet metal plates bent upon themselves at their vertical edges and engaging the bent edges of adjacent plates with a sliding fit, and a pivoted cover plate within said walls over the burners adapted to be moved to an upright position to the rear of the burners and adjacent the rear wall.
4. In a gas stove, a supporting cabinet having a top, gas burners mounted on said top, upright walls surrounding the gas burners, a pivoted cover plate within said walls over the burners and adapted to be moved to an upright position to the rear of the burners and forwardly of the rear wall, a bottom for the cabinet and a door between the top and bottom to give access to the space therebetween.
5. In a gas stove, a supporting cabinet comprising corner legs and walls enclosing the space included between said legs and detachably connected therewith, including a frame secured to the top of the legs, a plate carried by said cabinet, burners carried by said plate, upright walls carried by the cabinet around said burners, and a retractable cover plate over the burners and adapted to be moved to a position rearwardly of the burners and forwardly of the rear wall.
6. In a gas stove, a burner, a supporting cabinet for the burner comprising a frame including side and end members, legs secured to the frame at the junction of the side and end members and having pivotal connection with one of said members enclosing walls removably secured to the legs, upright enclosing walls for the burner, and a retractable cover plate over the burner adapted to be moved to an upright position to the rear of the burner adjacent the rear wall.
7. In a gas stove, a burner, a supporting cabinet for said burner comprising supports, a bottom and back wall carried by said support and hinged together, the back wall comprising upper and lower hinged sections, a shelf hinged to the lower section adjacent the top edge thereof and adapted to be moved to alignment with the lower section when the top section is folded back on the lower section.
8. In a gas stove, a burner, a supporting cabinet for said burner comprising supports, a bottom and back wall carried by said supports and hinged together, the back wall comprising upper and lower hinged sections, and a shelf hinged to one of said sections, said bottom and back walls and shelf adapted to be folded upon each other.

In testimony whereof I affix my signature. 75
HARRY CHILINGIRIAN.
